UNITED STATES PATENT OFFICE.

WILLIAM H. BULLOCK AND GEORGE B. FAYETTE, OF OSWEGO, NEW YORK, ASSIGNEES
OF FIVE-SIXTEENTHS TO AUGUSTUS P. MURDOCK, THREE-SIXTEENTHS TO OREL P.
KEENEY, FIVE-SIXTEENTHS TO SAID BULLOCK, AND THREE-SIXTEENTHS TO SAID
FAYETTE, ALL OF OSWEGO, NEW YORK.

ACCELERATOR FOR HOT-WATER SYSTEMS.

1,118,394.

Specification of Letters Patent.

Patented Nov. 24, 1914.

Application filed May 31, 1912. Serial No. 700,615.

To all whom it may concern:

Be it known that we, WILLIAM H. BULLOCK and GEORGE B. FAYETTE, citizens of the United States, residing at Oswego, in the county of Oswego and State of New York, have invented certain new and useful Improvements in Accelerators for Hot-Water Systems, of which the following is a specification.

10 Our invention relates to improvements in hot water heating systems, and consists of an accelerator adapted to operate automatically to establish rapid circulation of the heated water through the piping and radiators, with a corresponding high temperature, or to operate at a slower rate of circulation and reduced temperature, according to weather conditions, etc., and within the easy control of a valve controlled by 20 pass.

It has for its object to increase the efficiency of hot water heating systems, either new or old, where the circulation is sluggish, and is designed to prevent the undue 25 expansion and boiling of the water and to limit the pressure to a maximum of say ten pounds. When the temperature is raised beyond the boiling point of 212° and the pressure to say ten pounds, the temperature will 30 be correspondingly raised to about 240°, at which pressure the accelerator is designed to positively vent. Incidentally, the speed of circulation through the system will be increased about five fold, and the usual radiation surface may be reduced by from 10 to 15 per cent.

In the drawings illustrating the invention: Figure 1 is a view of the device in elevation, as installed in a system. Fig. 2 is an 40 enlarged central vertical sectional view through the accelerator in position for operation.

The accelerator A is of generally cylindrical form, comprising a main casing 2 having a cap 3 at its upper end, connected by a flange union 4, and connected at its lower end by pipe 5 with the boiler or heater and at its upper end by pipe 6 with the expansion tank 7, it being understood that these 50 elements are also connected with the circulation system embodying any suitable radiating means. The interior of the accelerator A is chambered above and below a trans-

verse diaphragm 8, providing the upper chamber 9 and lower chamber 10. Laterally 55 of the casing 2 is a by-pass chambered projection 11 communicating with upper chamber 9 and lower chamber 10 respectively, and provided with a transverse hand-operated valve or cock 12 having a port 13 and handle 14. Mounted in the diaphragm 8 is a brass bushing 15 having an opening 16 therethrough, centrally of the casing and provided at its upper portion with a surrounding valve seat 17. A valve 18 normally seats 65 thereon and is held to its seat by its hollow stem 19 and a coil spring 20, the pressure of which is varied by a temper nut 21, the spring being adapted to hold the valve 18 to its seat against any pressure up to say 70 ten pounds. Valve stem 19 is hollow, as stated, having a longitudinal circulation port 22 communicating at the upper end with the interior of check valve casing 23 containing the ball check valve 24 and having a lateral opening 25 through the stem below diaphragm 8. When the pressure from the heater through pipe 5 and in chamber 10 exceeds such limit, the valve 18 will be raised and the water will pass through to 80 the expansion tank 7.

For the purpose of effecting return circulation of the water when contracted or when the temperature and pressure are reduced, the ball check valve 24 normally seated in the interior of the valve casing 23, opens inwardly, due to excess of pressure in chamber 9. By this means, when the pressure below diaphragm 8 in chamber 10 is reduced, valve 24 will open, and the water 90 of the system will drain back through hollow stem 19 to its normal level.

When it is desired to utilize the accelerator in the manner of an open or gravity system, the cock 12 is turned to register port 95 13 with the upper and lower chambers 9 and 10 respectively, the water circulating therethrough without operation of the other parts just described. Such operation is utilized for heating in mild weather, and is 100 also useful in filling the system around the valves, preventing air locks and enabling filling under low pressure.

The device is comparatively simple in construction and operation, easy to install and 105 keep in order, noiseless in action, and so de-

signed that one standard size may be used with all systems. It will be understood, of course, that venting pressure can be changed with tension nut 21 to suit varying conditions or requirements, and that the device may be otherwise changed or varied by the skilled mechanic without departing from the scope of the following claims.

What we claim is:

10. 1. The combination with the circulating pipes of a water heating system, of a chambered casing having a valve seat and a valve thereon controlling circulation through the casing, said valve embodying in itself a 15 valve-controlled conduit extending through from one side of said valve seat to the other and consisting of a hollow stem having at its upper end a casing provided with a downwardly opening valve-seated port, a 20 check valve normally closing said port, and a surrounding spring engaging the lower end portion of said conduit and normally holding its valve on the seat of the chambered casing.
25. 2. Valve mechanism for an accelerator of the class described provided with a casing, a main circulation connection at each end of the casing, and a transverse diaphragm having a valve seated opening, consisting of a 30 vertically arranged valve stem having an upper integral valve portion for said opening and extending above and below said valve portion, said valve stem having an independent longitudinal circulating port through its center opening to the interior of the casing 35 below said valve portion and

having a downwardly directed valve-seated outlet opening at its upper end, a gravitating check valve closing said outlet opening, and a spring inserted between the under 40 side of the diaphragm and the lower end portion of the valve stem and normally holding it to its seat, substantially as set forth.

3. Valve mechanism for an accelerator of 45 the class described provided with a casing, a main circulation connection at each end of the casing, and a transverse diaphragm having a valve seated opening, consisting of a vertically arranged valve stem having an 50 upper valve portion for said opening and extending above and below said valve portion, said valve stem having an independent longitudinal circulating port through its center opening to the interior of the casing 55 above and below said valve portion, a check valve closing the upper outlet opening of said circulating port, an adjustable spring-retaining nut threaded on the lower end of the valve stem, and a spring inserted between the under side of the diaphragm and said nut adapted to hold the upper valve portion of said stem to its seat, substantially 60 as set forth.

In testimony whereof we hereunto affix 65 our signatures in the presence of two witnesses.

WILLIAM H. BULLOCK.
GEORGE B. FAYETTE.
